UNITED STATES PATENT OFFICE.

ROBERT H. JENSON, OF HOUSTON, TEXAS, ASSIGNOR, BY MESNE ASSIGNMENTS, TO BROWN METAL AND CORK COMPANY, A CORPORATION.

CASTING MACHINE.

Application filed September 19, 1927. Serial No. 220,418.

This invention relates to new and useful improvements in a casting machine.

One object of the invention is to provide a machine of the character described especially designed for the purpose of casting weights, or sinkers, from fusible metal, for fishing tackle.

Another object of the invention is to provide a machine of the character described having a mould composed of confronting jaws having complementary, registering, casting cavities wherein the sinkers are formed, or cast, with means associated with said jaws for grooving the sinkers, as cast, and means for automatically operating the jaws into active relation, to form the moulds and into inactive relation to release the cast sinkers therefrom.

Another object of the invention is to provide a device of the character described equipped with novel means for pouring the melted metal into the moulds.

With the above and other objects in view this invention has particular relation to certain novel features of construction operation and arrangement of parts an example of which is given in this specification and illustrated in the accompanying drawings wherein:—

Figure 1 shows a plan view of the machine.

Figure 2 shows a side view, partly in section.

Figure 3 shows an inside view of the mould jaw.

Figure 4 shows a sectional view thereof, taken on the line 4—4 of Figure 3.

Figures 5 and 6 show side and end views respectively of the completed sinker.

Figure 7 shows an end view of the machine, and

Figure 8 shows a transverse sectional view thereof.

Referring now more particularly to the drawings, wherein like numerals of reference designate similar parts in each of the figures the numeral 1 designates a stand on which the machine may be mounted. A suitable framework for the machine has been provided which, in the present instance, is shown as comprising the transverse end castings 2, 3, and the base 4 connecting said end castings, and mounted on said stand, and having the central opening 5. At one side of the framework there are the lengthwise spaced

tracks 6, 6, secured to the ends 2, 3. Slidably mounted on these tracks are the oppositely disposed jaw blocks 7, 7, to the facing ends of which the mould jaws 8, 8, are detachably secured. The jaw blocks 7 are retained on the tracks by means of the respective retaining flanges 9, 9, which are secured to said tracks and whose upper edges 10—10 override the lengthwise lateral shoulders 11 of said blocks. Fastened to the outer ends 60 of the blocks 7 are the guide rods 12, 12, which work through the aligned bearings 13, 13 carried by the respective brackets 14, 14, which are attached to the respective ends of the frame work. Fixed on the respective 65 rods 12, between the corresponding bearings 13 are the bearing collars 15. The outer end of each guide rod 12 has a cross yoke 16, secured thereto and pull springs 17, 17, connect the respective ends of these cross yokes 70 to the framework of the machine.

There are the transverse cam shafts 18, 18, at each end of the framework, mounted to rotate in the end bearings 19, 19 carried by said framework. Each cam shaft has a cam 80 20 fixed thereon, aligned, respectively with the roller bearings 22, 22 carried by the lower ends of the actuating levers 23, 23. Each lever 23, is pivoted, at an intermediate point, to the inner end of the corresponding arm 24, 85 which is anchored to the adjacent bracket 14, and the upper end of each lever 23 engages the inner side of the corresponding bearing collar 15.

The outer ends of the cam shafts 18 have 90 the bevel pinions 25, 25, fixed thereon which are in mesh with similar pinions 26, 26 which are fixed on the lengthwise drive shaft 27, rotatably mounted in suitable bearings carried by the framework. One end of the 95 shaft 27 has a spur gear 28 fixed thereon and operatively connected with the power shaft 29 through suitable reduction gearing designated generally by the numeral 30. The power shaft 29 carries a pulley 31 adapted 100 to receive a driving belt, (not shown).

As the drive shaft 27 is rotated the cam shafts 18, 18, will be correspondingly rotated, and the cams 20 will alternately actuate and release the corresponding levers 23. When actuated, these levers 23 will operate, through the mechanism described, to move the jaw blocks 7, and the jaws 8 carried thereby, outwardly, or apart, into inactive position, and when said cams release the levers 23 the 110

springs 17 will return the mould jaws into co-operating, or active position. The mould will thus be alternately opened and closed.

The inner, or confronting, sides of the 5 jaws 8 have complementary, matrices, or mould spaces, 81, positioned to register when the mould jaws are in active position, as above defined. The respective matrices have the usual gates 32 through which the casting 10 metal may be poured.

Above the mould there is a receiving pan 33, hinged at one end to the standard 34, which upstands from the frame work of the machine. This pan, when in open, or inactive 15 position, as shown in dotted lines in Figure 7, rests against the stop arm 35, upstanding from the frame work, and when in active position rests on top of the mould, with the oblong slot 36, in the bottom thereof, 20 aligned with the gates 32. The free end of said pan has a suitable handle 37 by means of which it may be moved into either of such positions.

Pivottally mounted on the standard 39 5 there is a hand lever 40 whose outer end is formed into a grip 41 and whose inner end is pivoted to the lower end of the link 42. This link supports the draw core which is pivottally connected to the upper end thereof 30 and whose upper edge works through an oblong slot 44 in the mould formed by spacing the lower parts of the jaws 8 apart, and into the matrices or mould spaces 81. This spacing is accomplished by forming lengthwise 35 spacer rib 45 along the upper edge of the inner side one of said jaws 8. The range of upward movement of the core 43 may be regulated by an adjusting screw 46 which is threaded downwardly through the outer end 40 of the lever 40 and whose free end is adapted to rest on the base 4.

In the operation the mould jaws 8 are reciprocated intermittently back and forth into and out of active position, or relation, by 45 means and in the manner hereinbefore described. When the mould jaws are in active relation the pan 33 may be swung forwardly onto the mould and the moulten metal poured therein and the metal will run through the slot 26 and the gates 32 into the matrices. These matrices are of such shape that end 50 lips 47, 47, will be formed on the sinker and the upper edge of the core 43 will form a lengthwise, line receiving groove 48, therein 55 between said lips. The weight of the outer end of the lever 40 is sufficient to hold said core in said position during the moulding process. The groove 48 is provided to receive the fishing line and the lips 47 are provided to be bent around said line to secure the sinker to the line.

While the sinkers are being cast the cams 20 are rotating idly and just before said cams actuate the levers 23 the core 43 is 60 withdrawn from the matrices, by manually

elevating the outer end of the lever 40 and the pan 33 is swung up into inactive position thus severing the small necks of metal connecting the cast sinkers with the supply of metal in the pan and discharging the 70 remaining contents of said pan therefrom. When the cams actuate said levers 23, the mould jaws 8 are moved apart, as hereinbefore described, and the cast sinkers drop from the matrices through between the 75 tracks 6 and through the opening 5 in the base, into any suitable receptacle provided to receive them.

The range of movement of the mould jaws toward each other may be regulated by 80 means of the adjustable stops 49, 49, adjustably connected to the outer ends of the rods 12 and adapted to abut the outer ends of the brackets 14.

While I have shown what I now consider 85 the preferred form of the invention it is obvious that mechanical changes may be made therein and equivalents substituted for the parts shown and I hereby reserve, the right to make such mechanical changes and 90 adaptations as may be comprehended within the scope of the appended claims.

What I claim is:—

1. A casting machine including a frame, a track thereon, relatively movable mould forming members on the frame, means normally holding the facing sides of said members in adjacent relation to form a mould, and for restoring such relation when the same is disturbed, said mould having a matrix provided with a gate and having an elongated bearing, a receiver for moulten metal associated with the mould and having a discharge opening, said receiver being movable into one position to align said opening with said gate, and into another position out of co-operative relation with said mould, mechanism for relatively moving said mould forming members apart to permit the release of the cast objects from said matrix 100 a draw core movable into and out of said matrix, said core being blade like in form, and being movable through said bearing into the matrix to form a groove in the cast object, and means for intermittently actuating said moving mechanism.

2. A casting machine including a frame, confronting jaws on the frame, means for normally maintaining the facing sides of said jaws in adjacent relation to form a mould, said mould have an internal cavity forming a matrix, said matrix having a gate and being provided with an oblong draw core bearing, means for introducing molten metal through the gate into the matrix, a 110 pivotally mounted lever, a draw core working in said bearing and connected to and operable by said lever and normally projecting into the matrix to form a groove in the object cast therein, and means for relatively 115

moving said jaws apart to automatically release the cast object therefrom.

3. A casting machine including a frame, confronting jaws on the frame, means for normally maintaining the facing sides of said jaw in adjacent relation to form a mould, said mould having an internal cavity forming a matrix, said matrix having a gate and being provided with an oblong draw core bearing, means for introducing molten metal through the gate into the matrix, a pivotally mounted lever, a draw core work-

ing in said bearing and connected to and operable by said lever, and means for relatively moving said jaws apart to automatically release the cast object therefrom, and a weight at the outer end of the lever forming means adapted to normally hold the draw core projected through said bearing in cooperating relation with the matrix where-
by a groove is formed in the cast object. 15 20

In testimony whereof I, have signed my name to this specification.

ROBERT H. JENSON.
